US00D431007S

United States Patent [19]

Trigiani et al.

[11] Patent Number: Des. 431,007

[45] Date of Patent: ** Sep. 19, 2000

[54] **APPARATUS FOR LEAK TESTING AND REFILLING AUTOMOTIVE COOLING SYSTEMS USING VACUUM**

[75] Inventors: **Phil Trigiani; Tony Ferraro**, both of Mississauga, Canada

[73] Assignee: **Uview Ultraviolet Systems, Inc.**, Mississauga, Canada

[**] Term: **14 Years**

[21] Appl. No.: **29/115,038**

[22] Filed: **Dec. 6, 1999**

[51] LOC (7) Cl. **10-04**

[52] U.S. Cl. **D10/101**

[58] Field of Search **D10/57, 101; 73/49.2, 73/49.7, 45.8; 374/208, 145, 146**

[57] CLAIM

The ornamental design of an apparatus for leak testing and refilling automotive cooling systems using vacuum, as shown and described.

DESCRIPTION

FIG. 1 is a top view of the apparatus for leak testing and refilling automotive cooling systems using vacuum.

FIG. 2 is a bottom view of the apparatus for leak testing and refilling automotive cooling systems using vacuum.

FIG. 3 is a left side view of the apparatus for leak testing and refilling automotive cooling systems using vacuum.

FIG. 4 is a right side view of the apparatus for leak testing and refilling automotive cooling systems using vacuum.

FIG. 5 is a front view of the apparatus for leak testing and refilling automotive cooling systems using vacuum; and, FIG. 6 is a back view of the apparatus for leak testing and refilling automotive cooling systems using vacuum.
